UNITED STATES PATENT OFFICE.

OTTO A. LEHMAN, OF HOBOKEN, NEW JERSEY.

CHATELAINE.

SPECIFICATION forming part of Letters Patent No. 683,611, dated October 1, 1901.

Application filed June 4, 1901. Serial No. 63,113. (No model.)

To all whom it may concern:

Be it known that I, OTTO A. LEHMAN, a citizen of the United States, and a resident of Hoboken, in the county of Hudson and State of New Jersey, have invented a new and useful Improvement in Chatelaines, of which the following is a specification.

My invention relates to an improvement in chatelaines; and it has for its object to provide a chatelaine which may be easily and effectually locked against unintentional removal from the waist, belt, or band of the wearer, the chatelaine being employed to support a bag or other article.

15 A further object is to provide a chatelaine having certain improvements in the construction, form, and arrangement of the several parts thereof.

20 A practical embodiment of my invention is represented in the accompanying drawings, in which—

25 Figure 1 represents in perspective my improved chatelaine in connection with an apparel-belt and supporting a bag, the chatelaine being in its closed or locked position. Fig. 2 is an enlarged front view of the chatelaine in its closed position. Fig. 3 is a back view of the same. Fig. 4 is a longitudinal section through the chatelaine in the plane 30 of the line A A of Fig. 2. Fig. 5 is a similar view of the chatelaine in its open position, and Fig. 6 is a partial front view of the chatelaine in its open position.

35 The chatelaine comprises a hook having an ornamental front plate 1 and a plain back plate 2 and a swinging spring-actuated locking-plate 3, hinged to the lower end of the back plate of the hook. The locking-plate and the hook form together an elongated loop 40 for the reception of an apparel-belt 4 or any other suitable band fitted to embrace the waist of the wearer.

45 The chatelaine-bag 5 is represented as supported by the chatelaine; but the chatelaine may be employed for supporting any other desired article instead of the bag.

50 The outer faces of the front plate 1 of the hook and the lock-plate 3 may be partially covered with leather 6, if so desired. The lower end of the back plate 2 of the hook is provided with a pair of uprising ears 7 and 8, which are preferably struck up from the

metal which forms the hook. The locking-plate 3 is substantially L-shaped in cross-section and the inwardly-projected branch of 55 the plate is provided with a pair of ears 9 and 10, which are hinged to the ears 7 and 8 on the back plate of the hook by means of a pin-tle 11. The free end of the plate is preferably provided with an ornamental thumb-piece 60 12, which serves the double purpose of a stop for limiting the inward movement of the locking-plate and also as a means for permitting the ready swinging open of the said plate. The means which I have shown for holding 65 the plate in its closed position under spring tension comprises a plate 13 of spring metal, riveted at 14 to the back face of the back plate 2 of the hook, near its lower end, which plate 13 is provided with two branches 15 and 16, 70 which bear against a downwardly-extended lip 17 at the inner end of the short branch of the L-shaped locking-lever. A third arm 18, between the arms 15 and 16 of the plate 13, is rolled into the form of a loop or eye for 75 securely locking an article-supporting ring 19 for use in attaching articles to the chatelaine.

By the use of the structure hereinabove described I am enabled to provide a chatelaine 80 which can be very quickly and easily attached to a belt or band and then locked against unintentional displacement therefrom.

The structure is materially simplified by providing a simple plate which serves the 85 double purpose of attaching the article-supporting ring to the chatelaine and also as a spring for the locking-plate.

It is evident that changes might be resorted to in the form, construction, and arrangement of the several parts without departing 90 from the spirit and scope of my invention. Hence I do not wish to limit myself strictly to the structure herein set forth; but

What I claim is—

95 1. A chatelaine comprising integral front and back plates forming a hook, a locking-plate hinged to the back plate and forming, when closed, a continuation of the front plate to complete an elongated loop, a supporting-ring and a spring carried by the back plate for yieldingly holding the locking-plate closed 100 and for connecting the ring to the back plate, substantially as set forth.

2. A chatelaine comprising integral front and back plates forming a hook, a spring-actuated locking-plate hinged to the back plate and forming, when closed, a continuation of 5 the front plate to complete an elongated loop and a thumb-piece overlapping the front plate serving as a stop to limit the inward movement of the locking-plate and also as a means for opening the same, substantially as set 10 forth.

3. A chatelaine comprising integral front and back plates, a locking-plate hinged to the back plate, a supporting-ring, and a spring-

plate secured to the back plate having an arm engaging the locking-plate for yieldingly 15 holding it closed and another arm wrapped around the ring for connecting the ring to the back plate, substantially as set forth.

In testimony that I claim the foregoing as my invention I have signed my name, in presence of two witnesses, this 29th day of May, A. D. 1901.

OTTO A. LEHMAN.
